UNITED STATES PATENT OFFICE

SAMUEL GREENHOUSE, OF BROOKLYN, NEW YORK

BOTTLING MACHINE

Application filed January 7, 1929. Serial No. 330,869.

This invention relates to bottle filling machines and while it may be used generally wherever it may be applied, it is particularly adapted for use in bottling carbonated water and other charged liquids.

The invention provides certain improvements in the subject matter disclosed in United States Letters Patent No. 1,686,811, October 9, 1928 in my co-pending application, Serial Number 46,791 filed July 29, 1925 and aims to provide new combinations with some of the elements disclosed in said applications, certain new elements, apparatus, parts and combinations arranged to co-act to provide a highly carbonated de-aerated product at a relatively low cost.

Other objects of the invention are to provide a tank which may be a permanent part of the bottle filling machine and used as a filling tank or which may be interposed between the carbonator or other source of carbonated water and a bottling machine and to provide new and improved means for regulating the height of the water and for maintaining a certain predetermined pressure within said tank.

The invention aims further to provide new and improved apparatus of economic construction which may be used in connection with the ordinary bottle filling machines and which will effectually remove free air from the carbonated liquid being bottled and provide a highly charged product with practically no waste of carbonic acid gas.

The above objects are accomplished and additional ends are attained by the novel construction, combination and arrangement of parts hereinafter described and illustrated in the accompanying drawing wherein I have shown a preferred form of the invention, it being understood that the invention is capable of various adaptations and that changes or modifications may be made or resort had to substitutions which come within the scope of the appended claims.

In the drawing like characters of reference are employed to designate like parts as the same may appear and in which:

The figure is a central, vertical, sectional

view of a tank constructed in accordance with this invention.

Proceeding now to a detailed description of the invention with reference to the particular adaptation thereof disclosed in the drawing, the numeral 10 is used to denote a tank which may be of any suitable construction and may be used as a filling tank of a bottling machine or interposed between a source of carbonated liquid and a bottling machine. The tank 10 is provided at the upper edge thereof with an outwardly projecting, circumferentially extending flange 11. The numeral 12 denotes a lid which is also provided around the outer edge thereof with an outwardly projecting flange 13 which is adapted to fit in the flange 11 with a suitable gasket 14 interposed therebetween. The flanges 12 and 13 are bolted or otherwise suitably secured together, thus enclosing a chamber 15. The tank 10 is provided on the bottom wall thereof with a threaded bore 16 in which is operatively secured an exteriorly threaded inlet pipe 17 which projects upwardly into the chamber 15.

The numeral 18 denotes a disk which is provided with a centrally positioned threaded bore 19 adapted to receive the inlet pipe 17. The disk 18 is mounted on the inlet pipe 17 with the threaded upper end of the pipe 17 operatively received in the bore 19. The numerals 20 and 21 denote nuts which are also threaded on the pipe 17 with the disk 18 received therebetween. The disk 18 is provided with a plurality of threaded bores 22 in which is operatively mounted the outlet tubes 23. The tubes 23 project downwardly from the lower face of the disk 18 and terminate in spaced relation to the bottom wall of the tank 10. The numeral 24 denotes a casting which is preferably circular in form and which is provided at the lower edge thereof with an outwardly projecting circumferentially extending flange 25. The flange 25 is positioned on the plate 18 with a suitable gasket 26 therebetween. The numeral 27 denotes screw bolts which are positioned through suitable bores in the flange 25 and secured in threaded bores in the disk 18 and

are operated to compress the gasket and form a fluid tight joint between the flange 25 and the disk 18 thereby forming the enclosed chamber 28. The casing 24 is provided on the upper face thereof with an axially arranged hub 29. The hub 29 is provided with a vertical bore 30 which extends axially therethrough and communicates with the cavity 28 in the casing 24.

10 By reference to the drawing, it will be seen that the pipe 17 projects upwardly above the bottom wall of the chamber 28. The numeral 31 denotes a valve head which is arranged to seat on the upper axial end of the pipe 17 so that it may be operated to close the upper end of said pipe. The numeral 32 denotes a valve stem which is suitably secured to the valve 31 and the numeral 34 denotes a tubular member which is slidably mounted in the bore 30 in the hub 29. The member 34 is provided with an axial bore 35 in which is slidably received the stem 32. The stem 32 is provided at the upper end thereof with a head 33 and a coil spring 36 is operatively mounted on the stem 32 so as to be compressed between the head 33 and the upper end of the member 34 to normally hold the lower end of the member 34 in forced contact with the valve 31. The hub 29 is provided at a point intermediate its length with suitable openings 37 for a purpose presently to appear. The member 34 is provided at a point positioned centrally of the openings 37 with an annular groove 38. The member 34 is reduced in diameter at the upper end thereof to provide an annular shoulder 39. The hub 29 is interiorly threaded at the upper end thereof and a plug 40 is operatively positioned therein. The plug 40 is provided with an axial bore 41 which extends therethrough. The reduced upper end of the member 34 is slidably mounted in the bore 41. The lower edge of the plug 40 is arranged to contact with the shoulder 39 to limit the upward movement of the member 34.

The numeral 42 is used generally to denote a lever or float arm which is pivotally secured as at 43 to the hub 29 with the inner end thereof projecting through one end of the opening 37. The inner end of the lever 42 is seated in the annular groove 38 whereby a movement of the lever 42 will cause a movement of the member 34. A float 44 is operatively secured to the outer end of the lever 42 whereby the lever 42 will be operated to move the member 34 downwardly closing the valve 31 when water within the tank has reached a certain predetermined level.

The casing 24 is provided on the upper wall thereof with a suitable threaded bore 45 in which is mounted the tube 46. The tube 46 is provided with a ball check valve 47 arranged to permit fluid to escape through the tube 46 and arranged to prevent any inward movement of fluid through said pipe into

said chamber 28. The tube 46 is extended outwardly and downwardly and is further provided at the lower end thereof at point above the water line with a spring operated ball check valve 48 which may be regulated by the screw 49 whereby a certain predetermined pressure is required to open the valve 48 and permit fluid to escape through the chamber 28. The lever 42 is provided with an arm 50 which extends to a point on the side of the hub 29 which is opposite the float 44. The arm 50 is provided on the free end thereof with a weight 51 which is arranged to balance or counteract the weight of the float 44. The arm 50 projects beyond the weight 51 to provide the extension 52. The tank 10 is provided on the bottom wall thereof at a point below the free end of the extension 52 with the threaded bore 53. The tubular member 54 is threaded in the bore 53 from the upper side of the bottom wall of said tank. The member 54 when operatively positioned in the bore 53 projects downwardly beyond the lower face of the bottom of the tank 10 and a suitable nut 55 is operatively threaded thereon. The member 54 is provided with a threaded bore 56 which extends axially therethrough. An exteriorly threaded tube 57 is operatively positioned in the bore 56. The tube 57 projects upwardly above the upper end of the member 54. The numeral 58 denotes a valve member which is in the form of a cylindrical weight having a bore 59 which extends therein from the lower axial end thereof and terminates in spaced relation to the upper axial end thereof. Suitable packing 60 is seated in said bore. The weight 58 is preferably formed of two parts with the lower part threaded on the upper part as shown in the drawings.

The bore 59 is enlarged at a point intermediate its length to provide a passage or groove 61 which extends entirely around the wall of said groove. The numeral 62 denotes vents which lead from the passage 61 through the wall of said weight and communicate with the cavity of the tank 10. The weight 58 is positioned on the upwardly projecting end of the tube 57 with the said upper end of the tube 57 received in the bore 59 and with the packing 60 positioned against the upper end of said tube.

The numeral 63 denotes a chain or other flexible member, one end of which is secured to the weight 58 and the other end secured to the free end of the arm 52. A spring 64 is positioned between the free end of the arm 52 and the upper axial end of the weight 58. The numeral 65 denotes a coupling member which is positioned on the lower end of the tube 57 and the numeral 66 denotes a nut which is threaded on the lower end of said pipe 57 to hold the coupling member 65 in forced contact with the lower end of the member 54. A suitable packing washer 67

is positioned against the upper and lower ends of the coupling member 65 so as to be compressed by operation of the nut 66 and form a fluid tight joint. The coupling member 65 is provided with a cavity 68 which extends entirely around the pipe 57. The coupling member is provided with an interiorly threaded nipple 69 having a bore 70 which communicates with the cavity 68. The tube 57 is provided with a bore 71 which extends through the wall thereof and communicates with the cavity 68. A tube 72 is operatively threaded in the nipple 69. The lower end of the pipe 57 is interiorly threaded and a needle valve 73 is operatively positioned therein so that it may be operated to close or regulate the size of the opening 71. The lid 12 is provided with the threaded opening 75 and a tubular member 76 is threaded therein from the lower face of said lid. The member 76 is provided with a bore 77 which extends axially therethrough. The bore 77 is enlarged at a point adjacent the lower end thereof and provided intermediate its length with the openings 78. The numeral 79 denotes a valve member which is mounted in the enlarged portion of said bore 77. The member 76 is interiorly threaded at the lower end thereof and a plug 80 is operatively secured therein. The plug 80 is provided with an axially arranged cavity 81 in which is mounted a coil spring 82. The lower end of the valve 79 is entered in the cavity 81 so as to compress the spring 82 and normally hold the valve 79 in an upward position. The numeral 83 denotes a tube which is suitably secured in the bore 77 of the member 76 and which projects downwardly into the enlarged portion of the bore 77. The valve member 79 is provided with an annular groove 84 in which is received the inwardly projecting end of the lever 85. The lever 85 is positioned through one of the openings 78 and is pivoted as at 86 whereby a movement of the lever 85 will open and close said valve. The lever 85 projects outwardly at a point adjacent the end of the lever 42 and is provided with a horizontal, right-angle extension which is positioned in the path of the lever 42 whereby a certain predetermined upward movement of the lever 42 will move the lever 85 upwardly and open the valve 79 which controls the lower end of the pipe 83. The numeral 88 denotes a gland member which is operatively threaded over the upwardly projecting end of the member 76 and which is provided with a suitable packing gland 89 which forms a fluid tight joint between the member 78 and the tube 83. The tube 83 is threaded in the member 76 and is provided in a plane above the gland member 88 with an operating wheel 90 whereby the tube 83 may be rotated to raise and lower the same in the bore 77 thereby providing convenient means for regulating the operation of the valve 79. The numeral 91

denotes a connecting member by which a tube 92 is coaxially and rotatably secured to the upper end of the tube 83 with the bores of the said tubes in communication. The lid 12 is provided with a suitable threaded bore 93 which is positioned directly above the bore 16 in the bottom wall of the tank. A plug 94 is threaded in the bore 93. The plug 94 is exteriorly threaded at the upper end thereof and an interiorly threaded casing 95 is operatively secured therein. The casing 95 is enlarged at the upper end thereof and is provided at the said upper end with an outwardly projecting, circumferentially extending flange 96. A diaphragm 97 is positioned on the flange 96 so as to entirely enclose the upper end of the casing 95. A top casing member 98 is provided at the lower edge thereof with a circumferentially extending, outwardly projecting flange 99 which is substantially the same size and area as the flange 96.

The top portion 98 of the casing is secured to the lower casing member 95 by means of the screws 100 which are entered through suitable bores in one of the said flanges and are operatively positioned in suitable threaded bores in the other flange. The plug 94 is provided with an axial bore 101 and a rod 102 is slidably positioned in said bore. The numeral 103 denotes a packing gland which is positioned in the upper face of the plug 94 so as to form a fluid tight joint between the plug 94 and the rod 102. The upper end of the rod 102 is entered in a suitable opening in the diaphragm 97 and is secured thereto by means of the nuts 104 which are threaded on said rod with a washer 105 positioned between each nut and the diaphragm 97. The spring 106 is mounted on the rod 102 and is compressed to bear against one of the washers 105 and the packing gland 103 to normally hold the rod 102 in an upright position.

The top casing member 98 is provided at the upper end with the suitable nipple 107 on which is threaded a four-way coupling member 108. The pipe 92 is operatively threaded on one of the horizontal nipples of the coupling member 108. A pipe 109 is threaded on the other horizontal nipple and a pressure gauge 110 is operatively positioned on said pipe. A tube 111 is threaded on the upwardly presented nipple of the coupling member 108. The tube 111 projects upwardly and is exteriorly threaded at the upper end thereof. A casing 112 is operatively positioned on the upper end of the tube 111.

The numeral 113 denotes a valve stem which is slidably mounted in the bore of the tube 111. The stem 113 is provided on the lower end thereof with a valve head 114 which is arranged to close the lower end of the tube 111. A coil spring 115 is mounted in the casing 112 and is compressed between the bottom of the casing 112 and a weight 116 which is positioned in the upper portion of the casing

112. The valve stem 113 extends upwardly and is normally positioned against the bottom of the weight 116. The weight 116 fits in the cavity of the casing 112 so that it will 5 act as a piston to push the stem 113 downwardly when air or gas under pressure is introduced into the upper portion of the chamber in the casing 112. The casing 112 is provided with a suitable lid 117 which is 10 threaded or otherwise suitably secured thereon. The lid 117 is provided with a suitable bore 118 in which is threaded an elbow 119. The pipe 72 is operatively threaded on said elbow.

15 With the valve 114 open, and the valve 79 closed, the diaphragm 97 holds the rod 102 in the position directly above and in spaced relation to the cap 33 on the rod 32. The lid 12 is also provided with a threaded bore 120 20 in which is threaded the escape valve 121. The escape valve 121 is set to provide a vent which will provide a constant escape of air from the chamber 15. The escape valve 121 is fully described in my co-pending application, Serial Number 633,983 and its uses and purposes are fully described in my pending applications Serial Numbers 560,876 and 46,791.

25 The tank 10 is provided on the bottom wall 30 thereof with a suitable opening 122 in which is threaded an outlet pipe 123. The outlet pipe 123 leads to a bottling machine or to an apparatus for filling bottles with liquid from within the tank 10. If desired, a number 35 of bottling machines or bottling devices may be operatively connected to the outlet pipe 123 and a high pressure and a low pressure machine may be operatively connected to the 40 outlet pipe 123 and operated at the same time by interposing a pressure reducer in the line leading to the low pressure machine.

45 Water is first introduced into the tank 10 through the pipe 17. When the machine is first started, the float 44 will be in a downward position, thus raising the member 34 and forcing the spring 36 upwardly against the head 33 and opening the valve 31. The downward position of the float 44 raises the arm 52 and opens the valve 58. The spring 81 50 holds the valve 79 in a closed position. The arm 85 is held in its normal horizontal position by reason of said spring 81. As water is introduced through the pipe 17 into the chamber 34, it flows downwardly through the 55 tubes 23 into the chamber 15 of the tank 10. As the chamber 15 fills with carbonated liquid, air or gas enters the openings 62 and escapes through the pipe 57 into the pipe 72. The pressure from this escaping air forces 60 the weight 116 downwardly opening the valve 114. The air thus escaping through the valve 114 escapes outwardly through the openings 134 in the casing 112. The tube 111 is provided on the interior face thereof with an 65 annular groove 135 and suitable openings 136

are formed in the wall of the tube so as to communicate with said groove. Approximately the lower half of the stem 113 is grooved to permit air to escape from the lower casing 98 through the grooves 137 which are 70 formed in said stem. The air in the upper portion of the casing 98 escapes outwardly through the opening 136 thereby releasing all pressure on the upper side of the diaphragm 97 and permitting the spring 106 to 75 force the diaphragm to its upward position. This permits the valve 31 to be operated freely without hindrance from the rod 102. As the water in the chamber 15 reaches the desired level, the float 44 closes the valve 58 80 and restricts the flow of water through the pipe 17. This however is not sufficient to entirely stop the flow of water from said pipe. As the water rises the arm 42 contacts with the arm 85 thus raising said arm and forcing the valve 79 downwardly opening the lower end of the pipe 83. The pressure within the chamber flows upwardly through the pipe 83 and creates a pressure in the upper casing 98. The pressure in the casing of the chamber 98 85 closes the valve 114 and forces the diaphragm 97 to its downward position, thus forcing the rod 102 downwardly and causes the same to engage the head 33 of the bolt 32, thus entirely closing the upper end of the pipe 17 and discontinuing the flow of water therethrough. As soon as the water within the tank is brought to the desired level, the float 44 will 90 bring the arm out of contact with the arm 85, thus permitting the spring 81 to close the valve 79. If the pressure within the chamber 15 becomes too great to permit the flow of liquid into the chamber 15, the float 44 will open the valve 58 and permit air to escape 95 through the pipe 72 as hereinbefore described. 100

105 In ordinary use, the float 44 is sufficient to regulate the operation of the valve 31 and the apparatus will operate under normal conditions without operating either the valve 79 or the valve 58. When ordinary apparatus is used the stopping of the bottling machine or any stoppage of the outlet tubes will cause the chamber 15 to fill to a level above the desired height. The apparatus herein described overcomes this objection and is particularly useful when the bottling machine or other apparatus connected to the outlet pipe 123 is stopped.

110 It will be seen from the foregoing description that I have provided a new and improved apparatus which is principally designed to remove free air and other undesirable gases from a liquid heavily charged with carbon-dioxide gas and that I have provided new and 115 advantageous improvements over the structure shown in my pending applications, Serial Numbers, 560,876, and 46,791.

120 Having thus illustrated my invention and described the same in detail, what I claim 125

as new and desire to secure by Letters Patent is:—

1. In a bottling apparatus of the class described, an enclosed tank, an inlet pipe leading thereto, a delivery pipe leading therefrom, a valve controlling said inlet pipe, a float arranged to operate said valve, additional means to positively close said valve, said means operable by a fluid pressure, means operable by said float to admit fluid pressure to said additional closing means and fluid pressure operated means to release the pressure from said additional closing means, said releasing means controlled by said float.
- 15 2. In a bottling apparatus of the class described, an enclosed tank, an inlet pipe leading thereto, an inlet valve on said pipe, a float arranged to operate said valve, additional means to positively close said inlet valve, said means operated by fluid pressure from within the tank, means operable by said float to admit fluid pressure to said additional closing means when the fluid within the tank has reached a certain level and means to release fluid pressure from said additional closing means and fluid pressure operable means controlled by said float for operating said releasing means.
- 30 3. In a bottling apparatus of the class described, an enclosed tank, an inlet pipe leading thereto, an outlet pipe leading therefrom, a valve on said inlet pipe, a float arranged to open said valve, additional means to positively close said inlet valve, said means operated by fluid pressure from within the tank, means operable by said float to admit fluid pressure to said additional closing means when the fluid within the tank has reached a certain level and means to release fluid pressure from said additional closing means and fluid pressure operable means controlled by said float for operating said releasing means when the liquid within the tank reaches a certain lower level.
- 35 4. In a bottling apparatus of the class described, an enclosed tank, an inlet pipe leading thereto, an outlet pipe leading therefrom, a valve on said inlet pipe, a float arranged to open said valve, additional means operated by fluid pressure to positively close said inlet valve, float operated means to admit fluid under pressure to said closing means when the fluid within the tank has reached a certain level and means to release fluid pressure from said additional closing means and when the water within the tank has reached a certain lower level and float controlled fluid pressure operable means for operating said releasing means.
- 50 5. In a bottling apparatus of the class described, an enclosed tank, a liquid inflow valve, a float arranged to normally operate said valve, fluid pressure operable means to positively close said valve and float controlled

means to admit an operating pressure to said positive closing means.

6. In a bottling apparatus of the class described, an enclosed tank, a liquid inflow valve, a float arranged to normally operate said valve, fluid pressure operable means to positively close said valve, a normally closed float controlled valve arranged to admit fluid under pressure to said positive closing means and float controlled means to release said fluid pressure.

7. In a bottling apparatus of the class described, an enclosed tank, a liquid inflow valve, a float arranged to normally operate said valve, fluid pressure operable means to positively close said valve, a normally closed float controlled valve arranged to admit fluid under pressure to said positive closing means and float controlled means to release said fluid pressure, the last named means also providing an escape for excess pressure within the tank.

8. In a bottling apparatus of the class described in combination, an enclosed tank, a liquid inflow valve, a float arranged to normally operate said valve, spring restrained fluid pressure operable means to positively close said valve, said positive closing means having a passage leading from said tank thereto, a normally closed valve controlling said passage and float operated means to open the valve controlling said passage.

9. In a bottling apparatus of the class described, in combination, an enclosed tank, a liquid inflow valve, a float arranged to normally operate said valve; spring restrained fluid pressure operable means to positively close said valve, said positive closing means having a passage leading from said tank thereto, a valve controlling said passage, a spring normally holding the last named valve in a closed position and means operable by said float to overcome said spring and open the valve in said passage.

10. In a bottling apparatus of the class described in combination, an enclosed tank, a liquid inflow valve, a float arranged to normally operate said valve; spring restrained fluid pressure operable means to positively close said valve, said means having, a passage leading from said tank thereto, a valve controlling said passage, a spring normally holding the last named valve in a closed position and regulatable means to provide a constant escape of fluid from the upper part of said tank.

11. In a bottling apparatus of the class described, in combination an enclosed tank, a liquid inflow valve, a float arranged to normally operate said valve; spring restrained fluid pressure operable means to positively close said valve, said positive closing means having a passage leading from said tank thereto, a valve controlling said passage, a

spring normally holding the last named valve in a closed position, and means operable by said float to release excess pressure from said tank.

5 In testimony whereof I have hereunto set my hand.

SAMUEL GREENHOUSE.
